ANTIAIRCRAFT GUN

Patrick J. Bohan, Sailor Springs, Ill., assignor of
thirty per cent to J. E. Pixley, East St. Louis,
Ill.

Application October 21, 1942, Serial No. 462,849

4 Claims. (Cl. 89—21)

This invention relates to anti-aircraft guns, and more particularly to improvements in the type of gun set forth in my United States Letters Patent No. 2,279,087, granted April 7, 1942.

The primary object of this invention is to simplify the operation of the breech block and the shell extractor, whereby the operation thereof may be easily and quickly brought about by a person operating a single hand lever, the latter also governing the distance the breech block may rotate and slide and to further reduce the number of parts over that employed in the gun of my patent above referred to, so that the manufacturing cost will be lower and to be less apt to become out of order.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is a top plan view, partly in section, illustrating a gun constructed in accordance with the present invention.

Figure 2 is a fragmentary vertical sectional view showing the gun ready to be fired, taken on the line 2—2 of Figure 1.

Figure 3 is a transverse sectional view taken on the line 3—3 of Figure 2.

Figure 4 is a transverse sectional view taken on the line 4—4 of Figure 2.

Figure 5 is a transverse sectional view taken on the line 5—5 of Figure 1.

Figure 6 is a transverse sectional view taken on the line 6—6 of Figure 2.

Figure 7 is a fragmentary sectional view showing the breech block in a locked position.

Figure 8 is a perspective view illustrating the extractor operating fork.

Referring in detail to the drawings, the numeral 5 indicates the breech housing, the support of which may be in accordance with that shown in my patent heretofore referred to or if desired some other form of support may be employed. The breech housing is of cylindrical shape provided at one end with a removable end wall 6 and its opposite end is closed permanently by a head 7 provided with a series of bores in which are mounted the butt ends of gun barrels 8 preferably five in number and tied together by a spider, as shown at 9. The bores of the head 7 also provide chambers for the reception

of shells 9' which extend into the barrels for a limited distance, the rims of the shells being positioned outwardly of the inner face of the head.

5 The housing 5 is provided with an opening 10 to permit the shells to be placed in the head and the barrels and to be removed therefrom after being fired. Opposed curved spaced flanges 11 are formed on the inner wall of the housing adjacent the head 7 and are employed for locking a breech block 12 in firing position and to permit the breech block to be released from firing position.

The breech block 12 is in the form of a sleeve 13 having a sliding fit with the housing 5 and one end thereof is closed by a head 14 of elongated formation, as shown in Figure 6, so that said head may be moved to lie between the flanges 11 and the head 7 for securing the breech block 12 in firing position. The shape of the head 14 will allow the breech block 12 to slide away from the head 7 when in the position, as shown in Figure 6, for the purpose of exposing the inner ends of the gun barrels to permit shells 25 to be either placed therein or removed therefrom.

Firing pins 15 are slidably mounted in the head 14 and are grouped to align with the detonators of the shells when the breech block 12 is in firing position. The firing pins 15 are secured to a plate 16 on which is secured a rod 17 slidably supported in brackets 15' mounted on the inner walls of the breech block 12. A coil spring 18 is mounted on the rod 17 and bears against one 30 of the brackets 15' and a collar 19 is secured on said rod for urging the firing pins normally into a position of being spaced slightly from the detonator ends of the shells when the breech block 12 is in firing position. The sliding movement of the firing pins in the stated direction is limited by the collar 19 abutting one of the brackets 15'.

An extractor 20 is provided for the shells and includes a plate 21 slidably mounted on the firing pins and interposed between the plate 21 and the head 14 on the firing pins are coil springs 22 acting to urge the plate 21 to the left in Figure 2. Hook-shaped elements 23 are pivoted to the plate 21 and operate in slots 24 formed in the head 14 and recesses 25 formed in the head 7. The hook-shaped elements 23 are engaged by spring pressed plungers 26 carried by the head 14 and acting to cause the hook-shaped elements to engage the rims of the shells when they enter the recesses 25 and during the movement of the plate 21 to

the right in Figure 2. The plate 21 is provided with a slot 27 in which is pivotally mounted a hand lever 28 that extends through an opening 29 in the sleeve 13 of the breech block and through an L-shaped slot 30' provided in the housing 5. A substantially U-shaped fork 31 is pivotally mounted in the slot 27 of the plate 21 and engages one face of the latter and has formed thereon a tapered lug 32 fitting in a notch 33 of a pivoted lever 34, the pivot of which is indicated at 35. The lever 34 is pivoted on the head 14 and the pivoted end thereof has a hook 36 engaging in a hook 37 on the pivoted end of the hand lever 28 so that when the hand lever is pulled rearwardly on its pivot in Figure 2 the lever 34 will be caused to rock on its pivot and impart pivotal movement to the fork 31 which in turn shoves the plate 21 forwardly in Figure 2 causing the hook shaped elements 23 to engage with the rims of the shell.

The hand lever 28 operating in the L-shaped slot 30' of the housing 5 will govern the rotary and sliding movements of the breech block. When the hand lever 28 is positioned in the branch A of the slot 30', the breech block will be in firing position and the hook-shaped elements 23 in retracted position. When the hand lever 28 is moved in the branch A of the slot 30' toward the branch B, the breech block 12 will be caused to rotate in the housing 5 disengaging the head 14 from the flanges 11 and moving the hand lever in the branch B of the slot 30' the breech block will be caused to slide to the left in Figure 2. The pull made on the hand lever 28 to slide the breech block to the left in Figure 2, causes the hand lever to pivot and operate the extractor so that the hook-shaped elements engaging the shells will extract the latter from the barrels in the head 7 so that on the sliding movement of the breech block to the left in Figure 2 the extracted shells may gravitate through the opening 19.

A firing mechanism 36 is mounted in the rear end of the breech block 12 for the purpose of operating the firing pins and is automatically moved into cocked position during the rearward movement of the breech block so as to be ready to be released on the breech block returning to firing position requiring only the operation of a trigger 37 for its actuation.

The firing mechanism 36 is in the form of journaled spaced connected plates 38, the journal thereof being in the form of a shaft 39 carried by the breech block. Formed on one of the plates are ears 40 and 41. The plates 38 are driven in a counter-clockwise direction by a clock-type spring 42 secured at one end to the shaft 39 which is fixed and having its other end secured to the plates 38. The ear 41 is adapted to strike the rod 17 for actuating the firing pin under the influence of the spring 42. To tension the spring 42, the ear 40 engages a stop 43 in the housing 5 when the breech block is moved rearwardly causing the plates 38 to rotate in a clockwise direction and are held in this position or cocked position by a leaf type spring 44 mounted in the breech block and engaging an ear on one of the plates 38. The trigger 37 which is in the form of a slidable pin engages the spring 44 to free the plates 38 to be driven in a counter-clockwise direction by the spring 42 for the actuating of the firing pins. The trigger 37 operates in an L-shaped slot provided in the housing 5 and indicated by the character 45.

The plunger of the trigger 37 is spring in-

fluenced, as shown at 47, requiring the operator of the gun only to press the plunger inwardly in order to free the firing mechanism 36.

The stop 43 is in the form of a bracket 48 supported on the end wall 6 of the housing 5 and has on its free end a pivoted member 49 lying in the path of the ear 40 of the plates 38 so that when the breech block 12 is moved rearwardly the member 49 engages the ear 40 and rotates the plates 38 in a clockwise direction to engage the ear thereof with the spring member 44 which is suitably mounted in the breech block. On the reverse movement of the breech block, the ear 40 may travel free of the member 49 due to its pivotal mounting on the bracket 48.

In operation to load the gun with shells, the hand lever is moved in the branch B of the slot 30' to cause a rearward sliding movement of the breech block so that the head 14 passes the opening 19 whereby the shells may be readily placed into the barrels of the gun as well as the bores of the head 7. This rearward movement of the breech block operates the firing mechanism into a cocked position. The hand lever is then shoved forwardly in the branch B of the slot 30' until the branch A is reached. The hand lever is then swung into the branch A causing a rotation of the breech block bringing the head 14 thereof into locking engagement with the flanges 11 and the breech block in firing position, that is the head 14 contacting the head 7. The firing pins are then aligned with the shells in the head 7 and barrels 8. To fire the gun the trigger is operated and on the operation thereof the firing mechanism 36 is freed so as to drive the rod 17 forwardly causing the firing pins to strike the detonators of the shells.

To unload the gun after being fired the operator moves the hand lever 28 through the branch A to the forward end of the branch B of the slot 30' unlocking the breech block from the head 7 so that on a movement of the hand lever into the branch B the hand lever will pivot actuating the extractor to bring the hook-shaped elements into engagement with the shells so that on the sliding of the breech block rearwardly the shells will be extracted and the firing mechanism cocked.

Thus it will be seen from the foregoing description, taken in connection with the accompanying drawings that the present arrangement of parts has greatly simplified the operation of the gun over that shown in my U. S. Letters Patent before mentioned, permitting the gun to be more economically constructed and less apt to become out of order. Also this construction requires less effort on the part of the operator for the operation of the gun than that required in the gun shown in said patent.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a gun, a breech housing having an L-shaped slot and including a bore and head at one end of said bore for supporting gun barrels in communication with the bore for receiving shells, a breech block slidably and rotatably mounted in the bore of the housing and having a head to abut the shells, firing pins carried by the head of the breech block, a firing means for operating the firing pins, an extractor slidably

supported by the firing pins and including hook-shaped elements slidably supported by the head of the breech block to engage with the shells, an operating means for the extractor and including a hand lever for the actuation thereof and extending through the breech block and through the L-shaped slot for the rotation and sliding movement of the breech block, flanges formed on the housing, said head of the breech block being of a shape to engage with the flanges on the rotation of the breech block in one direction for locking the latter against sliding movement and to become free of the flanges on the rotation of the breech block by the handle in another direction.

2. In a gun, a breech housing having an L-shaped slot and including a bore, gun barrels supported by the housing and in communication with the bore to receive shells, a breech block slidably and rotatably mounted in the bore of the housing, a head carried by the breech block to abut the shells, a firing means for the shells carried by the head, shell extracting means carried by the firing means and including a plate with hook-shaped elements pivoted thereto and slidable in the head to engage the shells, a pivotally mounted handle in the breech block and connected to the extracting means for the operation of the latter on pivotal movement of said handle and the latter extending through the L-shaped slot for the rotation of the breech block in either direction and for the sliding of the breech block in either direction.

3. In a gun, a breech housing having an L-shaped slot and including a bore, gun barrels mounted in the housing in communication with the bore to receive shells, a breech block including a cylindrical sleeve slidable in the bore and a head at one end thereof, said head being of elongated formation, flanges in the housing to be engaged and disengaged by the head during the rotation of the breech block in opposite directions, firing pins slidable in the head, a rod connected to the firing pins and slidably supported in the sleeve of the breech block and spring influenced in one direction, a spring operated firing means in the sleeve of the breech block to engage with the rod for operating the firing pins against the shells, a plate slidable on the firing pins, said head having slots, hook-

shaped elements pivoted to said plate and operating in the slots to engage the shells, a fork pivoted on the plate and engaging one face thereof, a hand lever pivoted to said plate and extending through the L-shaped slot, a pivoted lever connecting the hand lever to said fork, said hand lever being employed for movement in either branch of the slot for the rotation and sliding of the breech block in the bore and for the actuation of the hook-shaped elements into engagement with the shells by the pivotal movement of the hand lever during its initial movement in one branch of the slot for the sliding of the breech block in one direction.

4. In a gun, a breech housing having an L-shaped slot and including a bore, gun barrels mounted in the housing in communication with the bore to receive shells, a breech block including a cylindrical sleeve slidable in the bore and a head at one end thereof, said head being of elongated formation, flanges in the housing to be engaged and disengaged by the head during the rotation of the breech block in opposite directions, firing pins slidable in the head, a rod connected to the firing pins and slidably supported in the sleeve of the breech block and spring influenced in one direction, a spring operated firing means in the sleeve of the breech block to engage with the rod for operating the firing pins against the shells, a plate slidable on the firing pins, said head having slots, hook-shaped elements pivoted to said plate and operating in the slots to engage the shells, a fork pivoted on the plate and engaging one face thereof, a hand lever pivoted to said plate and extending through the L-shaped slot, a pivoted lever connecting the hand lever to said fork, said hand lever being employed for movement in either branch of the slot for the rotation and sliding of the breech block in the bore and for the actuation of the hook-shaped elements into engagement with the shells by the pivotal movement of the hand lever during its initial movement in one branch of the slot for the sliding of the breech block in one direction, and means mounted in the housing to engage the firing means for the cocking of the latter on the sliding movement of the breech block in one direction by the hand lever.
